United States Patent Office

Des. 185,719
Patented July 21, 1959

185,719

WATER HEATER

Pierre Pehau, Milan, Italy, assignor to Societa Italiana
Misuratori S.I.M.S.p.A., Milan, Italy

Application August 6, 1958, Serial No. 52,063

Term of patent 3½ years

(Cl. D81—2)

The figure is a perspective view of a water heater embodying my new design.

The side of the water heater not shown is a mirror image of the side shown and the top and rear are plain.

I claim:

The ornamental design for a water heater, substantially as shown and described.
